CLAIM

The ornamental design for a battery pack, as shown and described.

DESCRIPTION

FIG. 1 is a back perspective view of a first embodiment of a battery pack with folded away mini USB connector, iPhone connector, lightning connector and USB connector showing our new design;

FIG. 2 is a front perspective view thereof;

FIG. 3 is a back view thereof;

FIG. 4 is a top view thereof;

FIG. 5 is a bottom view thereof;

FIG. 6 is a left view thereof;

FIG. 7 is a right view thereof;

FIG. 8 is a front view thereof with keys attached to give sense of perspective;

FIG. 9 is a front and top perspective view of a second embodiment thereof with USB or mini USB installed;

FIG. 10 is a front and top perspective view thereof with USB installed;

FIG. 11 is a front and top perspective view thereof with key ring separated;

FIG. 12 is a right perspective view thereof with mini USB connector installed;

FIG. 13 is a right perspective view thereof with mini USB connector separated;

FIG. 14 is a front and bottom perspective view thereof;

FIG. 15 is a bottom and right perspective view of a third embodiment thereof with iPhone connector, micro USB connector or lightning connector separated;

FIG. 16 is a top and right perspective view with iPhone connector installed, and the key ring removed;

FIG. 17 is a top and right perspective view with iPhone connector separated, and the key ring removed;

FIG. 18 is a right perspective view with micro USB connector installed, and the key ring removed;

FIG. 19 is a right perspective view with lightning connector installed, and the key ring removed;

FIG. 20 is a right perspective view with lightning connector separated, and the key ring removed; and,

FIG. 21 is a right perspective view with iPhone connector installed, and the key ring removed, with an iPhone shown connected to give sense of perspective.

The broken lines shown in the drawings are included for the purpose of illustrating environmental structure and form no part of the claimed design.
